UNITED STATES PATENT OFFICE.

ANDREW J. McARTHUR, OF ATLANTA, GEORGIA, ASSIGNOR TO UNION FIBRE COMPANY,
OF WINONA, MINNESOTA, A CORPORATION OF MINNESOTA.

COMPOSITE WEDGE.

1,237,532.

Specification of Letters Patent. Patented Aug. 21, 1917.

Application filed December 3, 1915. Serial No. 64,924.

To all whom it may concern:

Be it known that I, ANDREW J. McARTHUR, a citizen of the United States, residing at Atlanta, in the county of Fulton and State 5 of Georgia, have invented new and useful Improvements in Composite Wedges, of which the following is a specification.

In a companion application for patent filed herewith, I have illustrated and described an insulated barrel which includes a series of flexible staves. These staves, except one, are first loosely arranged, edge to edge, about the inner periphery of a barrel and the last stave of the series, which 15 forms a key for the lining, is finally pressed into place.

The object of the present invention is to provide an efficient tool, particularly, though not exclusively, adapted to press such loosely 20 arranged staves together, so that an adequate space may be formed to freely receive the final or key stave and thus complete the annular lining.

My invention also includes various novel 25 features of construction which are herein-after particularly described and pointed out in the claims.

In the accompanying drawings, Figure 1 is a perspective view of the external wedge 30 (forming part of my invention), illustrated as used upon the inner periphery of a barrel; Fig. 2 is a perspective view of the complete device; Fig. 3 is a front elevation of the internal wedge; and Fig. 4 is an edge 35 view thereof.

The embodiment of my invention, illustrated in the accompanying drawings, comprises what I term an external wedge A and an internal wedge B, which, when in place, 40 is adapted to expand the members of the wedge A. Said external wedge A consists of two identical members 12 slidably connected at their ends by transverse links 13; the outer edges 14 of said members 12 are 45 curved longitudinally to correspond with the edges of the abutting staves which are to be spread. The length of both wedges A and B is substantially equal to that of the staves to be placed; the outer or convex surfaces 50 of both wedges correspond with the curvature of the inner periphery of the barrel to be lined and both wedges, for convenience in construction and manipulation, are formed in upper and lower sections

which are respectively articulated by means 55 of the hinges 11.

The adjacent or inner edges 15 of the members 12 taper toward each other, gradually converging as they approach the bottom. The front side of each member is 60 formed with an enlargement 16 at each end. The links 13, slotted longitudinally at 17, are secured at one end upon enlargements 16 by a pivot 18 and the other ends of the links are secured upon the enlargements 16 of the 65 companion members 12 by a pintle 19 passing through the slot 17 in said links respectively. To render the slidable connections between the links 13 and members 12 more 70 secure, I place a keeper 21 between the head of each pintle 19 and the corresponding link, and turn the ends 22 of said keeper to slidably embrace the edges of said link.

The edges of the internal wedge B are tapered toward its lower end, the slope of 75 said edges corresponding in degree with the co-acting inclined edges 15 of the adjacent members 12. The upper end of said wedge B is enlarged to form a driving head 23 and enlargements 24 and 25 are respectively provided upon the front sides of the upper and lower sections of said wedge B. The enlargement 24 is curved or beveled at its lower end and the enlargement 25 is similarly curved at both ends to facilitate the 80 adjustment of said internal wedge between the members 12 of the external wedge A. The upper edge of said enlargement 24 is square to form a shoulder 24^b adapted to catch beneath the upper link 13, when the 85 wedge B is lifted so as to remove the wedge A from the barrel with said wedge B. One of said members 12 is supplied at its upper end with a hook 27 to pass over the upper 90 edge of a barrel and support the wedge in 95 position to expand the staves.

In operation, the external wedge A is hung from the upper edge of the board, by means of the hook 27, within the vacant space to be filled by the final stave, the members 12 of said wedge being spread by hand to bear against the adjacent edges of the staves on either side of the gap in said lining, as clearly shown in Fig. 1. The internal wedge B is then inserted between the 100 members 12 of said external wedge A and forced downward between said members to position illustrated in Fig. 1. The forci-

ble insertion of said wedge B spreads the members 12 until the space occupied by the composite wedge is large enough to freely receive the final stave of the lining, whereupon the lining staves adjacent to the wedge are temporarily held apart by tacking the same to the barrel or otherwise securing them. The wedge may then be removed from the barrel, after which the final stave 10 is put in place and the adjacent staves released.

Having described my invention, what I claim as new and desire to protect by Letters Patent is:

15. 1. In a composite wedge, an external wedge consisting of two members comprising upper and lower halves hinged together, links pivotally connected at one end to one member and pivotally and slidably connected at the other end to the second member 20 and an internal centrally hinged wedge to spread said members.

2. In a composite wedge of the class described, an external wedge consisting of 25 two connected members having their outer sides curved to conform with the inner periphery of a barrel, the outer edges of said members being also curved to conform with the edges of adjacent lining staves and the

inner edges of said members gradually converging as they approach the bottom, and an internal wedge centrally hinged and designed to be inserted between the members of said external wedge so as to forcibly spread the same, the edges of the last mentioned wedge converging toward its lower end and adapted to co-act with the inner edges of said external wedge. 30 35

3. In a composite wedge, an external wedge consisting of two members formed with enlargements at their ends, said members comprising upper and lower halves hinged together, transverse links secured upon said enlargements to slidably and pivotally connect said members, an internal 40 wedge adapted to be inserted between the members of said external wedge to spread the same, enlargements on said internal wedge adapted to pass beneath said links so as to laterally adjust said internal wedge 45 with respect to the external wedge, one of said enlargements having a shoulder thereon designed to catch beneath the upper link and remove the external wedge when said internal wedge is lifted. 50 55

Whereof, I have hereunto subscribed my name to this specification.

ANDREW J. McARTHUR.
